UNITED STATES PATENT OFFICE

2,440,882

CIGARETTE HOLDER AND EXTINGUISHER

Adolphus F. Walton, Washington, D. C.

Application October 15, 1946, Serial No. 703,363

3 Claims. (Cl. 131—175)

1

My invention relates to smokers' articles and more particularly to a cigarette holder.

The object of my invention is to provide a cigarette holder consisting of a body having a bore adapted to receive and hold a cigarette provided at its rear end with a slightly frusto-conical counterbore adapted to receive exchangeably a wad of cotton or the like, and a removable mouth-piece.

Another object of my invention is to provide a cigarette holder of the character indicated above having wire guideways attached thereto and extending forwardly therefrom to receive a cigarette extinguishing cap slidably between them, adapted to be pushed onto the lit end of a cigarette to extinguish the same.

Other objects of my invention may appear in the following specification describing my invention, with reference to the accompanying drawing illustrating a preferred embodiment of my invention.

It is however, to be understood that my invention is not to be limited or restricted to the exact construction and combination of parts described in the specification and shown in the drawing, but that such changes and modifications can be made, which fall within the scope of the claims appended hereto.

In the drawing:

Figure 1 is an elevational side view of a cigarette holder according to my invention, the extinguisher cap being shown in full lines in inoperative position, a cigarette and the extinguisher cap in operative position being shown in broken lines.

Figure 2 is a top plan view of Figure 1.

Figure 3 is a sectional view taken on line 3—3 in Figure 1.

Figure 4 is a sectional view taken on line 4—4 in Figure 1.

Referring now in detail to the drawing, the cigarette holder forming the subject matter of my invention has a cylindrical body 10 provided on its inner or forward end with a bore 11 adapted to receive a cigarette 12. On its rear end the body 10 has a frusto-conical counterbore 12, the bigger diameter of which is at the rear end of the counterbore, which forms a shoulder 13 with the bore 11. A wad of cotton 14, or the like is located in the inner end of the counterbore 12 abutting the shoulder 13.

A mouthpiece 15 has on its inner end a frusto-conical portion 16 slidably fitting into the frusto-conical counterbore 12. The frusto-conical mouthpiece portion 16 forms a shoulder 17 with

2

the forward end of the main portion of the mouthpiece, and the outside diameter of the forward end of the main portion of the mouthpiece is equal to the outside diameter of the cylindrical body 10.

The mouthpiece 15 is provided with a narrow bore 18, the forward end whereof is flared as clearly shown at 19 in Figure 3.

An elongated U-shaped wire guide 20 has two comparatively long shanks 21 connected with each other on their forward ends by a cross piece 22.

The rearward portions of the shanks 21 are embedded in longitudinal grooves arranged diametrically opposite to each other in the circumferential surface of the body 10 and the ends of these rearward shank portions are bent inwardly at right angles and are embedded in the rear surface of the body 10 as shown at 23.

20 A clamp ring 24 is firmly placed around the cylindrical body 10 to hold the shanks 21 of the elongated U-shaped wire guide in place in the longitudinal grooves in the circumferential surface of the body 10.

25 A cylindrical extinguisher cap 25 is slidably arranged between the two shanks 21, which are located in longitudinal grooves provided diametrically opposite to each other in the circumferential surface of the extinguisher cap 25.

30 This cap is closed on its front end and the opening of its hollow end 26 is large enough to receive the forward end of a cigarette 12 therein, which may be inserted in the forward end of the bore 11 in the cylindrical body 10.

35 When a cigarette is being smoked through the cigarette holder described above, the nicotine and moisture is detained and absorbed in the cotton wad 14. To remove this wad and replace it with a clean one the mouthpiece 15 is removed 40 from the cylindrical body 10. By using a wad 14 the bore 18 in the mouthpiece 15 is kept clean and fresh.

When it is desired to extinguish a cigarette before discarding it, the cap 25 is slidably moved 45 into contact with the burning end of the cigarette, so that this end is arranged inside the hollow 26 in the cap 25 and the burning cigarette is extinguished by lack of oxygen.

Having described my invention, I claim as new and desire to secure by Letters Patent:

1. The combination with a cigarette holder including an elongated body having a pair of oppositely-disposed longitudinal grooves in the outer surface thereof; of a cigarette extinguisher 55 comprising a U-shaped wire guide having two

comparatively long shanks and a cross-piece connecting the front ends of the shanks, the shanks being arranged in said longitudinal grooves provided in said body, an extinguisher cap slidably arranged between the shanks and having a rearwardly open hollow adapted to receive the outer end of a cigarette mounted in the holder, the rearward ends of the shanks being bent inwardly at right angles and being embedded in the rear end surface of the body, and a clamp ring surrounding said body and said shanks to secure said shanks in the grooves in the body.

2. The combination with a cigarette holder including an elongated body having a pair of oppositely-disposed longitudinal grooves in the outer surface thereof, of a cigarette extinguisher comprising a U-shaped wire guide having two comparatively long shanks and a cross-piece connecting the front ends of the shanks, the shanks being arranged in said longitudinal grooves provided in the surface of said body, an extinguisher cap slidably arranged between said shanks and having a rearwardly open hollow adapted to receive the outer end of a cigarette mounted in the holder, and a clamp ring surrounding said body and said shanks to secure the shanks in the longitudinal grooves in said body.

3. The combination with a cigarette holder including an elongated body having a pair of oppositely-disposed longitudinal grooves in the outer surface thereof, of a cigarette extinguisher comprising a U-shaped wire guide having two comparatively long shanks and a cross-piece connecting the front ends of the shanks, the shanks being received in said longitudinal grooves of said body, and an extinguisher cap slidably arranged between the shanks and having a rearwardly open hollow adapted to receive the outer end of a cigarette mounted in said holder, said extinguisher cap having oppositely-disposed longitudinal grooves in its circumferential surface to receive said shanks slidably therein.

ADOLPHUS F. WALTON.
